UNITED STATES PATENT OFFICE.

MORRIS HERSCOVITZ, OF NEW YORK, N. Y.

CLOTHES-DRIER.

986,711.

Specification of Letters Patent. Patented Mar. 14, 1911.

Application filed August 26, 1910. Serial No. 579,070.

To all whom it may concern:

Be it known that I, MORRIS HERSCOVITZ, a citizen of the United States of America, residing in New York, in the borough of 5 Manhattan, county and State of New York, have invented certain new and useful Improvements in Clothes-Driers, of which the following is a specification.

The invention consists of a rotatable frame 10 provided with radial supporting arms supported by suitable bracket-arms outside of the window of the kitchen or laundry, and of a plurality of clothes-carrying frames on which the clothes may be hung after which 15 the frames are successively applied to the arms of the rotatable frame.

The invention consists further of the construction of the clothes-supporting frames, as will be fully described hereinafter and 20 finally pointed out in the claims.

In the accompanying drawings, Figure 1 represents a side-elevation partly in vertical section of my improved clothes drying frame. Fig. 2 is a plan view of the frame, 25 parts being removed. Fig. 3 is a vertical transverse section of one of the clothes-carrying frames detached from the arms of the rotatable frame, and Fig. 4 shows a longitudinal vertical section of one end of a 30 clothes-carrying frame.

Similar letters of reference indicate corresponding parts throughout the different figures.

Referring to the drawings, *a* represents 35 the rotatable frame of my improved clothes drier. The rotatable frame is suspended at the outer end of a bracket-frame *b* which is preferably formed of a horizontal arm *b*¹ and an inclined arm *b*², which arms are attached to a wooden bar or board *c*, which is secured to the outside of the wall at the side of the kitchen or laundry-window. The 40 projecting end of the bracket *b* is provided with a downwardly projecting journal *b*⁴ on which is rotatably mounted the center-disk *a*¹ of the frame *a*. The frame *a* comprises said center-disk *a*¹ and the radial arms *a*² supported thereby which are provided at their outer ends with detachable 45 collars *a*³, preferably of rubber or other elastic material. In place of these elastic collars screw-collars may be used, which may be screwed to the outer ends of the radial arms *a*².

To each radial arm of the rotatable frame *a* is applied a clothes-carrying frame *D*.

The clothes-carrying frame *D* is composed of two hanger-members *d*, which are provided at their upper portions with openings *o* for the radial arms *a*² and at their middle 60 portions with another set of openings *o*¹ and at the lower parts of their opposite sides with arc-shaped recesses *d*². Into the openings *o*¹ is inserted a clamping bar *e*, which is formed of two semi-cylindrical pieces 65 which are secured together at their ends by elastic collars *e*¹. In the side-recesses *d*² of the hangers are also placed clothes-carrying rods *f* formed of two semi-cylindrical sections with elastic collars *f*¹ securing their 70 ends together said side-rods being held in position on the hanger-frame by means of spring actuated pivoted clamping pins *f*¹, the upper ends of which are locked in position by wedge-shaped pieces *f*² which are 75 connected by short chains *f*³ to the upper ends of the hanger-members *d*, so that when the wedge-shaped pieces between the upper ends of the hanger-members and the upper ends of the clamping-pins are placed in position, 80 the clothes-carrying rods at the lower ends of the hanger-frames are securely held in position.

Suitable covers or hoods *g* for protecting the clothes-carrying frames *D* may be provided. These covers *g* are made of sheet metal and provided with longitudinal slots *g*¹ at the middle parts near their ends, which slots are adapted to receive screw-eyes *g*² screwed in the upper part of the hanger-members *d*. These eyes are then turned transversely to the slots thus holding the covers *g* against accidental displacement. These covers are mainly intended for the protection of the clothes-carrying frames in 95 the winter-season against snow and ice, but can be removed during the summer months of the year.

My improved clothes-drier is used as follows: All the clothes-carrying frames are removed from the radial arms of the rotatable frame to the inside of the kitchen or laundry. The clamping-rods are then removed from the hanger-frames and clothes *h* applied to the same by removing the elastic collars from the ends of the sectional rods, placing the clothes *h* between the semi-cylindrical rods, as shown in Fig. 3, and then applying the elastic collars to the ends of the same. The center rod is first placed in position in 110 the openings *o*¹ of the hanger-frames by passing first one end, then the other end,

through the openings of the hanger-frames, after which the elastic collars are applied to the ends of the clamping rod. The side clamping-rods are applied to the hanger-frames by first removing the wedge-shaped pieces, so that the clamping-rods can be placed in position between the lower recessed ends of the hanger-members and the spring-actuated clothes-pins, after which the 5 wedge-shaped pieces are inserted in position so as to securely lock the clamping-rods in position on the hanger-frames. The entire clothes-carrying frame is then placed in position on one of the radial arms of the rotatable table frame and the collars placed on the outer ends of the radial arms, so as to prevent the slipping off or detaching of the clothes-carrying frame therefrom. The rotatable frame is then rotated so that the next 10 radial arm is placed in position near the window for placing the next clothes-carrying frame on the same and so on, until all the radial arms of the rotatable frame are provided with clothes-carrying rods. The 15 clothes are then permitted to dry, and after they are dry, one clothes-carrying frame after the other is removed from the radial arms of the rotatable frame and placed inside of the kitchen or laundry. The clothes 20 are then removed from the clamping rods by removing one rod after the other from the hanger-frames and detaching the clothes from the same. The clothes-carrying frames are retained inside of the building, so that 25 only the rotatable frame with its radial arms is located outside of the building and exposed to the influence of the atmosphere.

The detachable clothes-carrying frames, of which as many are furnished as there are 30 radial arms on the rotatable frame, permit the fastening of the clothes to the clamping rods of the frame at the inside of the laundry, without leaning out of the window. The rotatable frame is arranged at a proper 35 level with the window opening so as to permit the convenient transferring of the clothes-carrying frames to the radial arms of the rotatable frame, likewise without the dangerous bending outside of the window-opening, so that the frames with the clothes 40

suspended thereon can be readily placed on the arms of the rotatable frame and removed therefrom with the clothes after they are dry. By the locking means on the hanger-frames, the clamping-pins of the clothes-carrying rods are rigidly held in position so that they cannot be detached from the hanger-frames even by a strong wind. 55

Having thus described my invention, I claim as new and desire to secure by Letters 60 Patent:

1. In a clothes-drier, a clothes-carrying frame comprising spaced hanger-members, having openings in their middle portions and alined recesses in their edges, cloth-carrying rods in said recesses, and clamping members pivoted to the edges of the spaced members and holding said rods in the recesses. 65

2. In a clothes-drier, a clothes-carrying frame, comprising spaced hanger-members having upper and lower openings and side recesses, sectional clothes-carrying clamping rods placed in said lower openings and said recesses, spring-pressed clamping-pins pivoted to the sides of said hanger-members and holding the clamping-rods in said recesses, and wedge-shaped pieces placed between the upper ends of said pins and the edges of said members for locking said clamping-pins 75 against the clamping-rods. 80

3. In a clothes drier, the combination of spaced hanger-members having, in their side edges outwardly opening alined recesses, and in their intra-marginal parts upper 85 openings for receiving supporting arms, and lower openings, clamping rods received in said recesses and lower openings, said rods comprising semi-cylindrical sections of equal length, and elastic collars on the ends of 90 said rods, and means for holding the rods in the recesses.

In testimony, that I claim the foregoing as my invention, I have signed my name in presence of two subscribing witnesses.

MORRIS HERSCOVITZ.
